UNITED STATES PATENT OFFICE

EDWIN J. MCILVRIED, OF CLEVELAND, OHIO, ASSIGNOR, BY MESNE ASSIGNMENTS, TO
WESTERN ELECTRIC COMPANY, INCORPORATED, OF NEW YORK, N. Y., A CORPOR-
ATION OF NEW YORK

WIRE DRAWING MACHINE

Application filed April 24, 1929. Serial No. 357,754.

The present invention relates to the art of wire drawing and particularly to attachments for wire drawing machines, whereby the efficiency and productivity of these machines may be increased.

In the use of the usual or ordinary type of wire drawing machines, it is frequently necessary to change the machine from one in which the wire is received upon spools to one in which the wire is laid up in open coils. In changing from spooling to coiling, it has been necessary to make extensive alterations in the delivery end of the wire drawing machine, which requires considerable time and labor, and it is the purpose of the present invention to make the operation of changing over more convenient and expeditious.

The present invention provides for a new and novel arrangement of the delivery end of a wire drawing machine, whereby the operator can change and adapt the machine for either operation in a comparatively short period and without necessitating the extended shut down of the machine. The invention is shown and described in its preferred form and in which form it can be changed over rapidly and economically.

While the description and drawings are detailed so as to enable the invention to be readily understood by those skilled in the art, it will be appreciated that changes and modifications may be made therein within the scope of the invention as set out in the claims.

In the drawings there is shown a wire drawing machine provided with the spooling and coiling apparatus, the machine being shown somewhat diagrammatically, as the details of the drawing machine are no part of the present invention, except as the same may be used in conjunction and combination with the improvement.

Figure 1 is a plan view of a wire drawing machine, as adapted for the spooling operation, showing the manner in which the invention is to be applied thereto.

Figure 2 is a section in the line 2—2 of Figure 1 along the capstan shaft showing the machine equipped for spooling.

Figure 3 is a similar section showing the

machine equipped for the coiling operation, showing the capstan removed and the block in place in the machine.

The wire drawing machine is indicated by the numeral 1. The main or worm shaft of 55 the wire drawing machine is indicated by the numeral 2, by being driven from the motor 3. In addition to driving the drawing rolls, this shaft extends through the machine and through suitable clutches and gearing and 60 drives the spool shaft 5 and the spool 6 thereon.

The shaft 2, is provided with the worm 8 which drives the worm gear 9 on the transverse shaft 10 mounted in the bearings 11 65 on the machine housing 12. The shaft 10 extends through the housing to provide a driving extension 15 on which is keyed and removably mounted the main or finishing capstan 16.

In spooling the wire the capstan 16 is mounted on the shaft 10 being held in position by the nut 18. The wire is given the requisite number of turns about the capstan and is then passed to the spool 6.

To change over to the coiling method, the upper part of the housing is provided with an opening 20, circular in form, and covered, when not in use by removable plate 21. When the cover is removed a ring 22 is placed over the opening 20, being properly located by means of a flange or rib 23, and held in position by bolts 24 which also pass through the block housing or casing 25. This casing surrounds the block or wire coiling drum 26. 85 Within the casing, and resting upon the ring 22 is a bearing ring 27 and attached to and depending from the ring 22 is a bearing bracket 28.

In the ring 27 and the bracket 28 are the 90 aligned bearings 29 and 30 respectively, in which is received the vertical shaft 32 on which the drum 26 is secured. Between the bearings the shaft 32 is provided with a bevel gear 34, which is adapted, when the parts are 95 assembled, to mesh with the bevel driving pinion 36 on the shaft 10. When the capstan 16 is removed it may be replaced by a collar 38.

The operation and advantages of the ap- 100

paratus will be readily appreciated. The change-over from the spooling to the coiling operation is made possible by removing the capstan 16, and the plate 21, and placing the block assembly in the opening 20, with the bevel gear 34 in mesh with the bevel gear 36. The change-over is made without disturbing the path of the wire, the receiving point in the block being coincident with the point 10 at which the wire passes on to the capstan.

What is claimed is:

1. In a strand working machine, means to provide interchangeable finished strand delivery means and finished strand take-up means comprising a housing, a drive shaft therein, a capstan adapted to be mounted on the shaft for delivering the finished strand, and a winding unit adapted to be driven by the shaft and to be removably mounted on 20 the housing as a unit, with the strand receiving point of the winding unit substantially coincident with the strand receiving point of the capstan and with the plane of rotation of the winding unit substantially perpendicular to the plane of rotation of the capstan.

2. In a wire drawing machine, means to provide interchangeable finished wire delivery means and finished wire take-up means comprising a housing, a drive shaft journaled 30 therein, a capstan adapted to be mounted on the shaft for delivering the finished wire, a drive gear on the shaft, said finished wire take-up means removable as a unit and comprising a secondary housing, a driven shaft 35 journaled in the secondary housing, a gear on the driven shaft, and a drum for laying up the wire in coil form mounted on the driven shaft within the secondary housing, said secondary housing adapted to be mounted on 40 said first named housing with the gear on said driven shaft meshing with the drive gear on the first named shaft and with the periphery of the drum substantially coincident with the wire receiving point of the capstan.

3. In a strand working mechanism, interchangeable strand delivery means and strand laying-up means comprising a housing having an aperture therein, a shaft extending within said housing, a capstan adapted to be mounted on the shaft external to said housing for delivering the finished strand, a transmission member secured to said shaft, said strand laying up means comprising a stationary member adapted to be secured to said 50 housing, a rotatable drum, a second shaft secured to said drum and extending through said stationary member, another transmission member secured to said second shaft and adapted to slidably engage said first mentioned transmission member, and means located between said stationary member and said second shaft for preventing movement between said stationary member and said second shaft in a direction parallel to said shaft 60 and permitting rotatable movement between 65

said stationary member and said second shaft, and said strand laying-up means positioned over and adapted to cover the aperture in said housing with the periphery of the drum substantially coincident with the strand receiving point of the capstan and detachable as a unit.

4. In a strand working mechanism, interchangeable strand delivery means and strand laying-up means, a housing having an aperture therein, a shaft extending within said housing, a capstan adapted to be mounted on the shaft external to said housing for delivering the finished strand, a transmission member secured to said shaft, said strand laying up means comprising a stationary casing, a rotatable drum located within the casing, a second shaft secured to said drum and extending through said casing, another transmission member secured to said second shaft and adapted to slidably engage said first mentioned transmission member, a bearing ring located between said drum and said other transmission member, and means including a second ring having a flange and adapted to 80 secure the casing of said detachable unit to the bearing ring and to said housing, and said strand laying-up means positioned over and adapted to cover the aperture in said 85 housing with the periphery of the drum substantially coincident with the strand receiving point of the capstan and detachable as a unit.

5. In a strand working mechanism optionally operable for receiving the strand on spools or laying it up in open coils, a housing having an aperture therein and adapted to optionally receive a strand laying up means or a removable cover, a shaft extending within said housing and having a portion thereof centrally located below the aperture in the housing, another portion of said shaft adapted to have a strand delivery unit secured thereto, a transmission member secured to said shaft and located beneath the aperture 100 in said housing, said strand laying up means comprising another shaft adapted to extend through the aperture in said housing and perpendicular to said first mentioned shaft, another transmission member secured to said 105 second shaft and adapted to engage said first mentioned transmission member, a drum secured to said second shaft, a stationary member between said drum, and said other transmission member having a flanged portion adapted to project within the aperture in said housing and adapted to be secured to said 110 housing, means located between said stationary member and said shaft for preventing movement between said stationary member and said second shaft in a direction parallel to said shaft and permitting rotatable movement between said stationary member and said second shaft, said last mentioned means comprising a bearing located between said 115 120 125 130

drum and said other transmission member
and a second bearing located on the other
side of said other transmission member from
said first mentioned bearing, said strand lay-
5 ing-up means removable as a unit and adapt-
ed to be secured to said housing with the
periphery of the drum substantially coinci-
dent with the strand receiving point of the
strand delivery unit.
